[57] CLAIM

The ornamental design for a dishwasher detergent dispenser, as shown.

DESCRIPTION

FIG. 1 is a top, front and left side perspective view of a dishwasher detergent dispenser showing our new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a bottom plan view thereof;

FIG. 7 is a top, front and left side perspective view of a second embodiment of our new design;

FIG. 8 is a top, front and left side perspective view of a third embodiment of our new design;

FIG. 9 is a front elevational view of the second embodiment;

FIG. 10 is a right side elevational view of the second and third embodiments;

FIG. 11 is a top plan view of the second and third embodiments;

FIG. 12 is a rear elevational view of the second and third embodiments;

FIG. 13 is a left side elevational view of the second and third embodiments;

FIG. 14 is a bottom plan view of the second embodiment;

FIG. 15 is a rear elevational view of the first embodiment;

FIG. 16 is a bottom plan view of the third embodiment; and,

FIG. 17 is a rear elevational view of the third embodiment.

FIG. 1.

FIG. 2.
